Inventor:

United States Patent Office.

FREDERICK CAJAR, OF NEW YORK, N. Y.

Letters Patent No. 65,167, dated May 28, 1867.

IMPROVEMENT IN CAR-SPRINGS.

The Schedule referred to in these Letters Patent and making part of the same.

Be it known that I, F. CAJAR, of the city of New York, county of New York, and State of New York, have invented a new and improved Coiled and Spiral Car-Spring and Buffer; and I do hereby declare that the following is a full and exact description thereof, reference being had to the accompanying drawings, and its corresponding figures and letters, of which—

Figures I, III represent elevations of my spring.

Figures II, IV represent sectional views of the same.

Figures I, II showing the spring in its natural position.

Figures III, IV the same when arrived at the point of the highest pressure of the burden.

Letters A to F designating the individual cones of the springs; *a* the outward, *b* the inward ribs or projections of the respective lower margins of the spring and its cones.

The nature, use, and operation of my invention will be developed at the first glance over the drawings, as it becomes plainly obvious thereby that by the means of said ribs *a* and *b*, owing to the increased strength or stiffness they impart to the sides of their respective cones, the "flattening" of the spring, or spreading out, viz, the extending of the base of the cones beyond their natural diameter is greatly, even entirely avoided; thus the whole effect of the spring secured; that, further, my ribbed cones cannot so easily and also deeply become "boxed" into each other, as this is the case with coil springs of former construction, and that, consequently, the friction which is produced by such an boxing, and which cannot but absorb a good deal of the force of the spring's resistance or elasticity (needed for counteracting the pressure of the burden) will be reduced by my improvement, and in accordance with the degree of curving the sides of the cones from an extensive plane to a mere line of friction. It will be also obvious that the spring itself will gain by said ribs in strength, steadiness, and power of action, especially if compared with a coiled spring of Harrison's patent, (patented August 24, 1858,) and one of equal size and thickness of metal. My spring, besides, represents in said ribs *a* and *b* two additional spirals as auxiliaries to the single spiral of coiled springs of said Harrison's and similar construction.

What I claim as my invention, and desire to secure by Letters Patent, is—

The improvement of coiled or spiral springs and buffers for cars, &c., by providing the lower margins of the coil, viz, of their individual cones, with the ribs or projections *a* and *b*, for the purpose and substantially as described above.

FR. CAJAR.
